UNITED STATES PATENT OFFICE

EDWARD W. LITTLE, OF INDIANAPOLIS, INDIANA

AIR DEFLECTOR

Application filed February 25, 1926. Serial No. 90,646.

This invention relates to heat deflectors and more particularly to a warm air filter therefor.

The primary object of this invention resides in the provision of means adapted to be associated with heat distributing units of building heating systems whereby warm air emitted from the heat distributing units will be purified prior to discharge into the rooms of buildings.

Another object of this invention resides in the provision of means adapted to be associated with heat distributing units of building heating systems so as to permit free circulation of the warm air emitted from the heat distributing units and separate foreign matter in the warm air prior to discharging the warm air into the rooms of the building.

A still further object of this invention resides in the provision of a heat deflector, adapted to be associated with heat distributing units of building heating systems, so as to check the flow of foreign matter carried by the warm air emitted from the heat distributing units and permit normal flow of pure air into the rooms of the building.

In addition to the aforesaid objects, this invention resides in the provision of a heat deflector with which is associated a warm air filter adapted to separate foreign matter from warm air and retain it for disposal when cleaning the filter.

Aside from the foregoing objects, this invention resides in the provision of a particularly constructed warm air deflector having a filter associated therewith, which not only functions in the capacity of purifying air passing therethrough, but is so arranged that it will function as a damper when manipulated out of normal position.

Among the objects heretofore set forth, this invention resides in the provision of a warm air deflector consisting of an association of elements which are readily assembled to present an ornamental adjunct to the heat

distributing units of building heating systems.

Included among the several objects of this invention an association of elements is introduced whereby the purification of warm air, emitted from the heat distributing units of building heating systems, is accomplished by directing it through or against a fibrous filter capable of retaining or collecting foreign matter carried by the air passing therethrough.

With these and other objects in view this invention resides in certain novel features of construction, arrangement and combination of elements to be hereinafter more fully set forth in the specification, illustrated in the drawings and pointed out in the appended claims and, while the disclosure depicts my present conception of the invention, the right is reserved to make such changes in construction as come within the scope of the claims.

In the accompanying drawings forming a part of this application:

Fig. 1 is a perspective view of a deflector constructed in accordance with this invention, showing the same associated with a register of a hot-air heating system;

Fig. 2 is an enlarged vertical sectional view thereof, approximately on line 2—2 of Fig. 1;

Fig. 3 is an enlarged horizontal sectional view of the deflector, approximately on line 3—3 of Fig. 1;

Fig. 4 is an enlarged cross sectional view, approximately on line 4—4 of Fig. 1;

Fig. 5 is an enlarged detail sectional view of a portion of the filter;

Fig. 6 is a front view of a modified form of a deflector as associated with a combined filter and damper;

Fig. 7 is a vertical sectional view thereof, approximately on line 7—7, showing the filter in normal position by full lines and in dotted lines as utilized in functioning as a damper;

Fig. 8 is a vertical sectional view of a de-

flector utilizing a plain fibrous or similar sheet of material as a filter.

In the present embodiment of this invention, the numeral 5 designates a hot air deflector of suitable design adapted to be associated with the heat distributing units of building heating systems and preferably consists of side members 6 having opposed channels 7 along their edges 8 for the reception of the edges 9 of a deflecting wall 10.

The aforesaid deflecting wall 10 has its forward and rear ends 11 and 12 rolled for the accommodation of rods 13 or the like, which are utilized to secure the side members 6 and deflecting wall 10 in rigid relation and prevent slippage of the deflecting wall in the channels 7.

Appropriately arranged in the rolled end 11 of the deflecting wall is a series of apertures 14 adapted to emit air directed against the deflecting wall.

Suitably secured in spaced relation beneath the deflecting wall 10 of the deflector is a filter 25, which consists of an apertured back plate 26, in opposed relation to the inner surface of the deflector wall, to provide an air passage immediately above the filter for conducting air toward and through the apertures 14 in the rolled end of the deflector wall 10. Suitably attached to the back plate 26 on that surface opposite to the air passage, thus formed, are a plurality of laterally extending baffles 27, which are formed from reticulated or other suitable material adapted to carry or support laterally extending catch basins 28 along their lowermost areas or therebeneath, so as to catch soot or other foreign matter collected or separated by a filtering material 29 confined between the walls of the baffles and above the catch basins.

Although the baffles 27 may be formed in any desired shape for association with a filtering material and the catch basins, the same are herein constructed in compound ogee configuration so as to provide pockets 30 for retaining the filtering material and catch basins.

To facilitate removal of the filter from the deflector, for cleaning, a bolt 31 or other suitable element is passed laterally through the same and side members 6 and retained against displacement by a thumb-nut 32.

With the aforesaid elements assembled, a hot air filtering deflector is provided for association with the heat distributing units of building heating systems, so as to direct the air, emitted or otherwise discharged therefrom, through the interstices of the reticulated material where it will pass through the filtering material, associated therewith, whereupon foreign matter, such as soot, coal dust or the like, will be retained by the filtering material and deposited in the catch basins therebeneath as it is accumulated.

In the modified form of this invention, as shown in Fig. 6, the deflector has its usual

open area covered with a reticulated material 32' or other ornamental screen and is adapted to hingedly support a filter 33, so as to be manipulated in close proximity to the deflecting wall thereof, to function as an air purifier, and lodged over the open area of the deflector, inward of the cover thereof, to function as a damper.

The deflector shown in Fig. 8 is of any suitable design and has a filter 36 likewise associated with its deflecting wall, and in this instance it is of a fireproof fibrous character supported beneath the deflecting wall, so as to collect foreign matter and permit air to flow freely therethrough.

Since deflectors of this character are especially designed to be associated with hot-air heating systems, their application as adjuncts to other heating systems is apparent and, while the type herein illustrated is of a stationary floor design, certain conditions necessitate minor alteration thereof to utilize the same on walls, in addition to pivotally securing them to their supports, and therefore the right is reserved to construct them to meet demands in their successful operation.

With this invention fully set forth, it is apparent that a deflector is introduced which will readily function to purify warm air passing therethrough and, through the particular association of elements, the cost of manufacture will be reasonable.

What I claim and desire to protect by Letters Patent is:

1. An air deflector of the character set forth, the combination of reticulated hollow baffles disposed in spaced relation to the deflecting surface of the deflector and extending outwardly therefrom, filtering material associated with the baffles, and catch basins positioned at the lower edges of the baffles.

2. An air deflector of the character set forth, having its deflecting wall provided with a series of apertures at its front end, a corrugated foraminous baffle having its corrugations extending laterally beneath the deflecting wall of the deflector, a catch basin at the lowest part of each corrugation, and an air outlet passage between the baffle and deflecting wall of the deflector.

3. An air deflector of the character set forth, the combination of a plurality of laterally extending baffles formed of reticulated material, an apertured back plate supporting the baffles and disposed in spaced relation to the deflecting wall of the deflector, catch basins supported on the lowermost walls of the baffles, filtering material housed by the baffles, and an air exit passage between the back plate and deflecting wall of the deflector.

4. In an air deflector of the character set forth, the combination of a corrugated foraminous baffle plate associated with the deflecting wall of the deflector, filtering material disposed in the corrugations of the fo-

raminous baffle plate and catch basins supported by the foraminous baffle plate at the lowermost portions of the corrugations thereof.

5 5. The combination of an air deflector having an open front portion covered with a screen, and an air filter pivoted within the deflector to swing over and away from said opening.

10 In testimony whereof I affix my signature.
EDWARD W. LITTLE.
